UNITED STATES PATENT OFFICE

167,893

TUMBLER HOLDER

Michael Hallward, Swampscott, Mass., assignor to Styron Corporation, Milford, Mass., a corporation of Massachusetts

Application November 29, 1951, Serial No. 17,556

Term of patent 14 years

(Cl. D4—3)

To all whom it may concern:

Be it known that I, Michael Hallward, a subject of the King of Great Britain, residing in Swampscott, Essex County, Commonwealth of Massachusetts, have invented a new, original, and ornamental Design for a Tumbler Holder, of which the following is a specification, reference being had to the accompanying drawings, forming a part thereof.

Figure 1 is a perspective view of a tumbler holder showing my new design; and Figure 2 is a side elevational view thereof as seen from the right of Figure 1.

I claim:

The ornamental design for a tumbler holder,
substantially as shown.

MICHAEL HALLWARD.
